AUTOMOBILE LOCK

Filed April 26, 1935

UNITED STATES PATENT OFFICE

2,169,796

AUTOMOBILE LOCK

Victor L. Gilpin, Baltimore, Md., assignor to Gilpin Autolock Corporation, a corporation of Maryland

Application April 26, 1935, Serial No. 18,444

3 Claims. (Cl. 70—252)

This invention relates to improvements in locks, especially motor vehicle locks, and its objects are as follow:

First, to provide an automobile lock in which there is means under control of a key to secure the locking bolt both in the locking and unlocking positions, said means being broadly considered herein collectively as consisting of an eccentric or off-centered ring, a pair of detents, one of them being a switch-closer, and a relatively fixed shoulder on which the switch-closer can either ride or against which it can abut, all of which is presently explained.

Second, to provide an automobile lock in which the foregoing means locks the bolt in the locking position, then secures the bolt in the unlocking position in this way that said means prevents the projection of the bolt to the locking position until the key is turned to enable such projection, the locking lever having a latitude of movement while said bolt is secured in the unlocking position in which said lever can be shifted back and forth across "start", "run" and "stop" positions as may be required by operating conditions.

Third, to provide positive operation for the locking bolt, that is to say instead of depending on the spring to project the bolt to the locking position (which in fact it does) there is a separate cam-operated pin in control of the bolt, first by compressing the spring and so projecting the bolt to the locking position, second by pressing back on the bolt and making the spring follow the bolt to the unlocking position.

Fourth, to utilize the foregoing cam-operated pin as a switch opener and closer, these functions agreeing with the locking and unlocking positions of the bolt for which said pin is responsible as previously pointed out.

Fifth, to use the means under control of the key, mentioned in the first object, for the additional purpose of securing the cam-operated pin in its switch-opening and switch-closing positions (corresponding with the locking and unlocking positions of the bolt), the two purposes of said means being directly related to what is herein called the hollow lever shaft, the ability to turn the shaft one way or the other to produce the locking and unlocking positions of the bolt depending on whether or not the foregoing locking means is so set by the key as to permit or prevent said turning.

In the drawing:

Figure 1 is a plan view of the lock, as seen

from the driver's position, the parts being in the locked position.

Figure 2 is an elevation of the lock as seen from the right or key end.

Figure 3 is a longitudinal section taken on the line 3—3 of Figure 2.

Figures 4, 5, 6, 7, 8, 9 and 10 are cross sections taken on the lines 4—4, 5—5, 6—6, 7—7, 8—8, 9—9 and 10—10 of Figure 3 illustrating the various parts in detail, bearing in mind that so far all views show the mechanism in the locked position.

Figure 11 is an elevation of the inside of the insulating cover plate, particularly showing the contact strips.

Figure 12 is a partially sectional and elevational view of the hollow lever shaft.

Figure 13 is a detail plan view of a part of the same shaft.

Figure 14 is a cross section similar to Figure 20 but showing the parts in the running position.

Figure 15 is a detail perspective view of the switch closer, this being one of the pair of detents previously mentioned.

Figure 16 is a detail perspective view of the other detent of the pair.

Figure 17 is a detail elevation of the outside flange of the hollow lever shaft.

Figure 18 is a detail plan view of a portion of the housing showing the arcuate slot.

In carrying out the invention provision is made of a lock casing, generally designated 1, which comprises a hub 2 to receive the customary tubing (not shown) of a steering post, said lock casing including means 3, 4 by which it is clamped to the tubing, there being a more or less customary bracket 5 to be secured to the instrument board (or elsewhere) on the vehicle. At one side of the hub 2 (either right or left) there is a bolt cylinder 6. This has an integral, segmented switch housing 7. The inner edge of this housing has a continuous rabbet 8 (Fig. 3) which receives the correspondingly formed part of an insulating cover plate 9. This plate carries a pair of binding posts 10, 11 (Fig. 3) near one end (Fig. 5), and a single binding post 12 near the other end.

These binding posts are the connectors for ignition and starter circuits. A wire 13 leads from the binding post 10 to one side of the ignition circuit (not shown). A wire 14 leads from the binding post 11 to one side of the battery, or other source of current (not shown), the other side of the battery being connected with the other side of the ignition circuit. A wire 15

40

45

50

55

55

leads from the binding post 12 to one side of the starter motor (not shown), the other side of said motor being connected with the second side of the source of current.

5 On the inside of the cover plate there are contacts 16, 17 (Fig. 11). These are fastened to the respective binding posts 10, 11. The contact 17 has a high place 18 with an adjacent valley 18a, which high place, when pressed upon by the cam-operated pin, closes the ignition circuit and one side of the starter circuit, maintaining said closure during the "start" and "run" positions of the locking lever. The free end of the contact 16 has a tread place 19 which, when depressed 10 by the switch-closer, closes the other side of the starter circuit keeping it closed only in the "start" position. At this point it is desired to explain 15 that the arrangement of contacts 16, 17 is chiefly intended to show one style. The binding posts 20 and contacts can be concerned with a variety of circuits, and it is not so material what the circuits are or how they are opened and closed, the principal thing being the controlling functions which the cam-operated pin and switch-closer 25 exercise in the sequence that is presently set out.

On the inside of the bolt cylinder 6 the construction is as follows: A hole 20 (Fig. 3) in the left end communicates with a bore 21. This bore merges into a counterbore 22, the point of 30 emergence forming an annular abutment 23. The counterbore 22 is enlarged at 24 to form part of a spring chamber, the end wall 25 of the enlargement having a hole 26 (Fig. 8) into which one end of the spring is set for an anchorage.

35 A groove 27 in the cylinder 6 communicates with the bore 21 and extends longitudinally of the bore (Fig. 3). This groove is both a securing groove for the securing detent and a guide groove for the cam-operated pin. Said groove registers 40 (Fig. 4) with a slot 28 on the other side of the cylinder 6, at least in part. This slot is shouldered at 29, and it merges into a cylindrical enlargement 30 at which the shoulder disappears (Fig. 3).

45 Said slot 28 forms an opening between the bore 21 and the inside of the housing 7. A second slot 31 in the cylinder 6 also forms an opening between the bore 21 and the inside of the housing 7. This slot follows the circular contour of the cylinder 6 and is arcuate as the consequence 50 (Fig. 5). The slot 28 extends longitudinally of the cylinder (Fig. 3). The two slots are at right angles to each other. One wall of the slot 31 has a shoulder 32 (Figs. 3 and 5). The shoulder is 55 arcuate like the slot. It is approximately one half as long as the slot and a little more than half as deep. This construction provides a stop 33 at one end of the shoulder. The clear place beyond the stop 33 provides space in which the 60 switch-closer has latitude or play to open and close a switch without disturbing the locking bolt from its unlocking position. The ends of the slot 31 are shaped to conform to the switch-closer which works back and forth therein. That end 65 of the slot farthest from the shoulder 32 has a lateral radial passage 34 (Fig. 18) which makes room for the lugs of the pair of detents when these are inserted in the assemblage of the parts.

A pair of V-grooves 35, 36 is cut into the 70 surface of the bore 21 (Figs. 5, 6 and 14). In this instance the V-groove 35 is spaced 50° from the groove 27, center to center, in the clockwise direction, and the V-groove 36, 20° from the V-groove 35. These grooves dog the securing de- 75 tent in the "stop" and "run" positions of the

lock. A pin-ended screw 37 (Fig. 8) is driven into the cylinder 6 so that its pin end aids in retaining the hollow lever shaft. A second pin-ended screw 38 (Fig. 9) is driven into the cylinder 6 to form a spring stop. A plate 39 (Fig. 1), 5 secured to the outside of the cylinder bears the legends Run, Start, Lock, Stop. These legends can be applied to the cylinder otherwise than by means of the plate, for example, the surface can either be embossed or impressed with the letters. 10

The hollow lever shaft 40 (Fig. 12) is turnably contained by the cylinder 6. It is of two principal diameters, the small one providing a sleeve 41 which fits the bore 21 (Fig. 3), the large one providing a hub 42 which fits the counterbore 15 22. The perpendicular annular face 43 (Fig. 13) between the sleeve 41 and hub 42 movably engages the abutment 23 so that when the shaft 40 is turned the face 43 rubs against the abutment 23. An annular groove 44 in the hub 42 (Fig. 12) 20 contains the pin end of the screw 37 (Fig. 8), thereby assisting in retaining the shaft 40 as previously stated. An annular reduction 45 in the hub 42 matches the enlargement 24 in the counterbore 22 and completes the chamber for the 25 spring 46.

This is a coil spring, and it is composed of several convolutions. Its ends are bent straight in the axial direction of the cylinder 6, one of the ends 47 (Fig. 8) being anchored in the hole 26, 30 the other end 48 (Fig. 9) extending forwardly beyond the open right end of the cylinder 6 but resting against the stop 38. The shaft 40 has an outside flange 49 with an integral lever 50. It is by means of the lever that the shaft 40 is 35 turned.

On its inside perpendicular surface 51 (Fig. 17) the flange 49 has an arcuate groove 52 into which the spring end 48 (Fig. 9) projects, said end extending forwardly beyond the stop 38 into 40 the groove (Fig. 10). When the lever 50 is turned as far as possible in the counter-clockwise direction to register the "lock" position (Fig. 1) the left end of the arcuate groove 52 (Fig. 10) will engage the projecting end 48 of the spring. 45 A radial hole 53 (Fig. 17) in the hub 42 is drilled so closely to the flange 49 that a channel 54 is formed in the surface 51. Said surface 51 comes quite close to the open right end of the cylinder 6 when the parts are assembled (Fig. 1), the 50 channel 54 then making room for the insertion of a stiff wire for the depression of a spring pin which occupies the hole 53.

A circular rabbet 55 (Fig. 3) contains the flange 56 of the plug cylinder 57. One cylindrical side of this cylinder is grooved at 58 (Fig. 3) for a short distance from the inner end of the cylinder to contain the end of a stud 59 which is set in the hub 42 (Figs. 3 and 12) and projects 60 into the interior of the hub. This arrangement prevents turning of the plug cylinder 57 relatively to the hub 42. Said cylinder is held in the hub by the spring pin 60 (Fig. 10) which extends from the cylinder 57 into the hole 53 65 (Fig. 17). This pin is pressed outwardly by a spring, and when the pin snaps into the hole 53 the cylinder 57 is held. Upon desiring to obstruct the plug cylinder 57 a stiff wire is inserted in the channel 54 and pushed against the pin 60 70 to depress the pin and so enable pulling out the plug cylinder 57.

The previously mentioned interior of the hub 42 (Fig. 12) is now identified as the bore 61. This bore ends in a wall 62. This wall has a 75

central opening 63 which is concentric with the bore 61. The opening 63 communicates with a T-slot 64 (Fig. 13) which comprises the cylindrical portion 65, the wing passages 66 and the 5 lug passage 67. The latter is made deep enough so as to cross the central opening 63 (Fig. 13). This lets the detent lugs ride across the opening 63, and this is necessary as is presently brought out. The T-slot 64 is in communication with the 10 bore 68 of the sleeve 41 by means of a center hole 69 (Fig. 12). The purpose of this hole is to admit a stiff wire for pressing back the spring plug of the locking bolt during the assemblage of the lock parts.

15 There is a pair of cam slots 70 in the sleeve 41. Each consists of a relatively long spiral portion (Fig. 13), ending in a pocket 71. The walls of each pocket are directed annularly of the sleeve 41 so that when the cam-operated pin occupies 20 the pockets the shaft 40 can be turned in the zone of the "start" and "run" positions without disturbing the cam-operated pin which thereby holds the starter circuit closed.

A stud 72 (Fig. 12), also secured to the hub 25 42 and projecting into the bore 61, provides a stop. A disc 73 (Fig. 7) turnably fits in the bore 61 but has enough of its perimeter cut away to provide heels 74, 75 to engage the stud 72 in the "lock" and "start" positions of the lever 30 shaft 40. The point of the stud 72 occupies part of the peripheral space provided by the cut away perimeter. The disc 73 has bearing against the wall 62 (Fig. 3). On the side opposite to the wall the disc has a transverse groove 76 (Fig. 7) 35 across its center. On the side next to the wall it has a concentric boss 77. This boss turns in the central opening 63, the surface of which provides a bearing. The boss has an eccentric or off-centered ring 78. This ring projects into the 40 T-slot 64.

The groove 76 contains the spline 79 of an adapter 80 which fits between the disc 73 and the plug cylinder 57 (Fig. 3). The adapter has a groove 81 in the side opposite to the spline 79, 45 and this groove contains the spline 82 of the key plug 83. This key plug is revolvably carried by the plug cylinder 57. It has a passage 84 (Fig. 2) for the key 85 (Fig. 1). Because of the fact that the key plug can consist of any known 50 kind of either the pin or leaf tumbler types the details of its internal construction are evaded in Figures 8, 9 and 10. It is considered sufficient to say that the key plug is not capable of being turned unless a properly constructed key 85 is 55 first inserted all the way.

A pair of detents 86, 87 (Figs. 15 and 16) occupies the T-slot 64 (Fig. 3). The detent 86 is the previously mentioned switch closer. The detent 87 is the securing detent. They have 60 cylindrical mid ribs 88, 89 respectively. These mid ribs have lateral wings 90, 91 which are slidable in the wing passages 66 (Fig. 13). The engagement of the wings with said passages prevents turning of the detents. The respective 65 mid ribs have lugs 92, 93. These lugs are in confronting positions. They are situated at the near extremities of the detents. They work in the zone of the lug passage 67 (Fig. 13), and are permanently embraced by the eccentric ring 78 (Fig. 3). The turning of the eccentric by means of the key 85 shifts the detents up and down. The detent 86 has an insulating cap 94. The 70 detent 87 has a bevelled point 95 (Fig. 16). The cap and point are remote from each other.

75 There is a cut-out 96 in one side of the mid

rib 88 (Fig. 15). The bottom of the cut-out is flush with one side surface of the lateral wings 90 so that there is a common smooth surface straight across. The cut-out is occupied by the shoulder 32 (Figs. 4 and 5) when the lock is in the "lock" position. At this time the detent 87 is projected into the groove 27. It is held there by a stiff spring 97 (Fig. 3) the ends of which occupy deep central communicating bores in the detents 86, 87. The cam-operated pin 98 (Fig. 3) 10 crosses the hollow shaft 40, its ends projecting through and beyond the cam slots 70 into the groove 27 and slot 28. The largest part of the pin extends from the shoulder 29 to the bottom of the groove 28, and beyond the shoulder 29 the 15 reduced end of the pin has an insulating cap 99 which is situated inside of the housing 7 in position to actuate the contact 17.

The locking bolt 100 (Fig. 3) is slidable in the bore 68 of the hollow shaft 40, its outer end being 20 projectable through the hole 26 into a locking position. Near its inner end it has a pair of straight, matching slots 101 through which the pin 98 extends. A spring 102 presses a spring 25 plug 103 against the side of the pin. This plug is actually the foundation for the spring, and the purpose of the spring is to enable yielding of the locking bolt in case the hole (not shown) in the steering post is not immediately found. The bolt can be moved toward the locking position, and by 30 then turning the steering wheel a little to one side or the other the bolt will snap into the hole when registration occurs.

Reverting to the hollow shaft 40, the outside flange 49 carries a pointer 104 (Fig. 1) which is 35 movable over the plate 39 to indicate the various legends.

The operation is readily understood. A majority of the views of the drawing show the lock in the "lock" position (Fig. 1). As long as the 40 point of the securing detent 87 remains in the groove 27 (Fig. 5) it is not possible to turn the hollow shaft 40 by means of the lever 50, and unless this shaft is turned it is impossible for the cam slots 70 to draw the bolt 100 inwardly 45 to the unlocking position. In order to unlock, insert the key 85 into the key plug 83 and turn clockwise 180°. The key is then held in the plug by the key and tumbler formations. An initial reverse turn is not possible because the heel 74 50 (Fig. 7) is against the stud 72. In making the clockwise turn the heel 75 is brought over against the stud 72.

The 180° turn of the key correspondingly turns the disc 73 180° so that the eccentric ring 55 78 is transferred from the bottom position (Fig. 7), so to speak, to the top position. The detent 86 stays where it is because it is held by the shoulder 32. The securing detent 87 is moved inwardly out of the groove 27 because of the 60 action of the eccentric ring against its lug 93. The spring 97 is thus placed under additional tension. The hollow shaft 40 is now free to be turned.

This turn is clockwise, and the extent of the 65 initial turn is 90°. In this initial turn the pointer 104 (Fig. 1) will go from "lock" to "start". Notice that the left end of the arcuate groove 52 (Fig. 10) in the flange 49 of the hollow shaft 40 is against the end 48 of the spring. The spring 70 tension is counter-clockwise, so that the end 48 presses against the stop 38. 70° of the foregoing turn is consumed, so to speak, by the groove 52, and at the end of the 70° turn which matches the registration of the pointer 104 with "run" 75

(Fig. 1) the right end of the groove 52 will have come into engagement with the spring end 48. The spring is then put under tension during the remaining 20° turn. In other words, the right 5 end of the groove 52 picks up the end 48 while the pointer moves from "run" to "start". The first part of the turn of the hollow shaft 40 is free, the last part under spring tension. Therefore, when the operator releases the lever 50, having moved the pointer to "start", the hollow 10 shaft automatically turns back counter-clockwise until the pointer 104 indicates "run", in which position the shaft is detained by the engagement of the point 95 (Fig. 14) of the detent 15 87 with the V-groove 36. The shaft is then no longer under spring tension, the spring end 48 (Fig. 10) being back against the stop 38, and the right end of the groove 52 merely containing the spring end.

20 Go back to the beginning of the clockwise turning of the hollow shaft 40. The cam slots 70 operate upon the pin 98 immediately so that it is shifted toward the right. In bearing against the right closed ends of the slots 101 in the bolt 25 100 said bolt is moved inwardly to the unlocking position. The cap 99 depresses the contact 17 and closes the ignition circuit and one side of the starter motor circuit. As soon as the detent 30 86 (Fig. 15) gets beyond the shoulder 32 (Fig. 14) it immediately springs outwardly under the tension of the spring 97 (Fig. 3). The cap 94 then rides the inside of the cover plate 9, and when it reaches the tread place 19 in the "start" 35 position (which is the end of the 90° turn of the hollow shaft 40), the remainder of the starter circuit will be closed. When the operator lets go of the lever 50 the spring 46 automatically turns the shaft 40 to the "run" position, as previously stated, keeping the ignition circuit closed but 40 opening the starter circuit (Fig. 14).

Should the operator desire to stop the motor he will turn the lever 50 back 20° in the counter-clockwise direction until the pointer 104 registers with "stop" (Fig. 1). The point 95 of the 45 detent 87 will then rest in the V-groove 35 (Fig. 5). The pin 98 (Fig. 3) is displaced far enough to the left by the cam slots 70 to cause the insulating cap 99 to occupy the valley 18. This opens the ignition circuit. But as far as turning 50 the lever 50 back all the way to the "lock" position is concerned it is not possible to do this until the key 85 is turned counter-clockwise 180°. It is only upon such turning of the key 55 getting it back to its original position, that it is possible to withdraw the key. The pointer may then remain on "stop", and the lever 50 can be turned either clockwise, or counter-clockwise with respect to "stop". But should it be turned counter-clockwise until the pointer registers with 60 "lock" the lever will become immovable.

The reason for this is that until the key is turned the then extended detent 86 is obstructed by the stop 33 of the shoulder 32 (Fig. 5) so that the lever is limited at the "stop" position. 65 Upon turning the key counter-clockwise 180° as just stated, the eccentric ring 78 is moved from the top position as it was previously called for convenience, to the bottom position (dotted lines, Fig. 7). This moves the lug 92 inwardly, and the detent 86 with it until the cut-out 96 registers with the shoulder 32 again.

Now the way is clear for the clockwise and counter-clockwise turning of the lever to each side of "stop", as well as the remaining full turn 70 of the lever in the counter-clockwise direction to

"lock", and when the pointer 104 again indicates "lock" the detent 87 will snap into the groove 27 and secure the hollow shaft in the "lock" position.

From what has just been stated it is clear that the bolt 100 is secured in the unlocked position as well as the locked position. When in the unlocked position it is prevented from being moved to the locked position by virtue of the shoulder 32 (Fig. 5) obstructing the detent 86. The detent 10 10 cannot be depressed until the eccentric ring 78 is turned and the eccentric ring cannot be turned unless the key is turned. Therefore, the eccentric ring 78, the detent 86 and shoulder 32 collectively constitute means under control of the 15 key 85 securing the bolt 100 in the unlocked position.

The operating zone of the pointer 104 (Fig. 1) in which the lever 50 has play is across the legends "start", "run" and "stop". The motor 20 can be started, run and stopped as many times as desired without locking the steering post. It is for this purpose that the cam slots 70 terminate in the pockets 71. These provide for the play or latitude of movement without affecting 25 the pin 98. While the pointer is within the foregoing zone the lever 50 cannot be turned counter-clockwise beyond "stop" without first turning the key 85 counter-clockwise 180°. Then the lever can be turned counter-clockwise until the pointer 30 indicates "lock" and whereupon the parts will be secured in the locked position.

I claim:

1. A lock comprising a locking bolt and an electrical switch, said switch comprising at least 35 one contact and a movable switch-closer, a spring which tends to press said closer to a circuit-closing position, a shoulder which is fixed relatively to the switch-closer and with which said closer is engaged to hold the closer in a circuit-opening position against the tension of the spring, there being a space beyond the shoulder providing a zone of independent movement for the closer, and means by which to simultaneously move the bolt to an unlocked position and to 40 move the closer clear of the shoulder and into said zone, whereupon the released spring presses the closer into circuit-closing position on the contact, said closer than being movable in said zone to off and on positions with respect to the 45 contact and acting as a detent against the shoulder which then obstructs said means from returning the bolt to a locking position.

2. A lock comprising a locking bolt and an electrical switch, said switch comprising at least 55 one contact and a movable switch-closer, a spring which tends to press said closer to a circuit-closing position, a shoulder which is fixed relatively to the switch-closer and with which said closer is engaged to hold the closer in a circuit-

opening position against the tension of the spring, there being a space beyond the shoulder providing a zone of independent movement for the closer, means by which to simultaneously move the bolt to an unlocked position and to 60 move the closer clear of the shoulder and into said zone, whereupon the released spring presses the closer into circuit-closing position on the contact, said closer then being movable in said zone to off and on positions with respect to the 65 contact and acting as a detent against the shoulder which then obstructs said means from returning the bolt to a locking position, and means 70 which is worked by a key to act on the closer so that it opens the circuit, recompresses the spring 75

and lines up for re-engagement with the shoulder, whereupon the first means can be operated to return the bolt to the locking position.

3. A lock comprising a locking bolt, a lever shaft and means to move the bolt to locking and unlocking positions through the instrumentality of the shaft, and means under control of a key

first to secure the bolt in its locking position, second to secure the bolt in its unlocking position, said means requiring operation by the key each time before the lever shaft can be used to move the bolt from a given position.
